ROLLER AND KEY FOR PRINTING PRESSES

Fred Ossing, Cleveland, Ohio

Application May 15, 1931. Serial No. 537,568

3 Claims. (Cl. 101—348)

The invention relates to improvements in inking rollers for printing presses and particularly to an improved shaft construction for such rollers.

5 The rollers in common use on what are known as job presses comprise a steel shaft on which is cast a resilient roller, the roller being a glue-gelatine composition or specially prepared rubber. Slidably received on the ends of the roller 10 shaft are guide rollers which operate on guides or roller-ways at each side of the press. The movement of the guide rollers over these guide-ways rotates the resilient rollers. The guide rollers are removable from the shaft by merely sliding them 15 longitudinally and are prevented from rotating on the shaft when slid into place by projections which are struck out of the shaft itself, the guide roller having a key-way into which one of the projections fit.

20 After being used for some time the rollers become dead and must be recast, the same shaft being used over and over again. It has been found that the projections which are struck from the shaft itself are soon worn or broken off and 25 the shaft rendered useless.

It is the object of my invention to provide a shaft construction which includes a removable key of a particular form which may be readily replaced when worn so that the shaft of the 30 roller may be used indefinitely.

A further object is to provide a construction in which the shaft may be of uniform diameter whereby to reduce expense.

A still further object is to provide means on 35 the key which will abut against a cooperating means formed in connection with the guide rollers for positioning said rollers on said shaft.

In the drawing, Fig. 1 is an elevation of an inking roller with a shaft and key constructed in 40 accordance with my invention, one end being shown in section; Fig. 2 is a longitudinal view through one end of the shaft in preferred modification; Fig. 3 is a section on line 3—3 of Fig. 2; Fig. 4 is a view similar to that of Fig. 2 of a 45 modified form and Fig. 5 is a section on line 5—5 of Fig. 4.

The numeral 10 indicates schematically tracks upon which the guide rollers 11 ride. The 50 rollers 11 are slidably received on a shaft 12 and are held against rotation with reference thereto by means of a key indicated generally by the numeral 13. The shaft 12 is covered between the guide rollers 11 by the glue-gelatine or rubber composition indicated by the numeral 14.

55 In the modification illustrated in Figs. 2 and 3,

the shaft 12 is provided with a shallow keyway 15 and spaced transversely extending openings 16 and 17. The key 13 is generally U shaped, being provided with extensions 18 adapted to be received in the openings 16 and 17. It will be understood that the projections 18 have a driven fit whereby to be frictionally held in position. The key 13 has at the end thereof nearest the end of the shaft 12 a level portion 19 and is provided intermediate its ends with a projection 20 defining a shoulder at the end of the portion 19. The guide roller 11 is provided with a keyway adapted to receive the portion of the key 13 which extends from the projection 20 toward the end of the shaft 12. The composition covering 70 14 on the shaft 12 extends substantially to the projection 20 whereby when the roller 11 is positioned by the key, it will be adjacent the end of such composition covering. It is to be understood that the keyway 15 may be omitted in this 75 modification.

In the modifications of Figs. 4 and 5, the openings 21 are positioned nearer the end of the shaft 12 and the key 13 is received entirely or substantially entirely within the guide roller 11. To 80 this end, the guide roller is provided with a keyway which is deeper at one end than the other provided with a keyway 22 whereby to receive the projection 20 up to a certain point and there having its shoulder 23 adapted to abut against said 85 projection 20. The keys are of identical construction in both modifications and the only differences are, as is clear from the drawing, those already pointed out. It is to be understood that a keyway corresponding to that 15 may be provided in the modification of Fig. 4.

While I have shown and described certain illustrative modifications of my invention, I wish it understood that I am not limited to the details thereof except in accordance with the terms of 90 95 the appended claims.

Having thus described my invention, what I claim is:

1. An inking roller construction including, a shaft, a key associated with said shaft, said key 100 and said shaft including means whereby said key is held against motion with respect to the shaft, a guide roller on said shaft and provided with a keyway adapted to receive said key, said key being provided with means adapted to abut said 105 guide roller for positioning the same, said key being received substantially entirely within said guide roller.

2. An inking roller construction including, a shaft of substantially uniform diameter, an open- 110

ing extending transversely through said shaft, a key having a projection extending into said opening and being of a size to be frictionally held therein, a guide roller on said shaft and provided with a shouldered keyway adapted to receive said key, said key being provided with means adapted to abut said guide roller for positioning the same, said key being received substantially entirely within said guide roller.

10 3. An inking roller construction including, a

shaft of substantially uniform diameter, a pair of spaced openings extending therethrough, a key having a pair of projections tightly received in said openings and a shoulder intermediate its ends, a guide roller on said shaft and provided with a shouldered keyway adapted to receive said key, said key being received substantially entirely within said guide roller, when said shoulders are in abutting relation.
